KNOCKDOWN SCAFFOLD

Clair F. Maroney, Ralph W. McGrew, and Daniel I. Weisz, Ellwood City, Pa., assignors to Beaver Art Metal Corporation, Ellwood City, Pa., a corporation of Pennsylvania

Application December 6, 1949, Serial No. 131,428

9 Claims. (Cl. 304—2)

1

This invention relates generally to knock-down scaffolds and, in particular, to an improvement on the connections shown in Patent No. 2,435,171 and Patent No. 2,483,862 for securing the diagonal braces or stays to the spaced rectangular end frames of such scaffolds in order to form a rigid self-sustaining structure.

Knock-down scaffolds are used extensively but as made prior to the invention covered by patents aforesaid, they required considerable time and labor as well as the use of tools for erection and dismantling. It is the object of this invention to provide a connection between the braces and end frames even simpler and easier to manipulate than the type shown in said patents.

In a preferred embodiment of the present invention there are provided gusset plates at the junction of the horizontal and vertical members of the end frames. These plates have slots extending therewith from the exposed edge, adapted to receive the end of a brace or stay. The brace is provided with a head at each end and a flange spaced inwardly thereof. The head is preferably of square cross section. Between each head and flange there is an end portion of substantially square cross section adapted to fit snugly within the slot in the gusset plate. A gravity latch or locking member which may be in the form of a hook is pivoted to the gusset plate so as to engage an edge of the head of the brace when the end portion is inserted into the slot in the gusset plate.

A more complete understanding of the invention may be obtained from the accompanying drawings which illustrate two preferred embodiments of the invention.

In the drawings,

Figure 1 is a section through the horizontal members of one end frame of a scaffold showing the ends of diagonal braces secured thereto.

Figure 2 is a section on the line 2—2 of Figure 1.

Figure 3 is a partial elevation of one end frame of a scaffold having the invention applied thereto.

Figure 4 is a section through the horizontal members of one end frame of a scaffold showing the ends of diagonal braces secured thereto by a different embodiment of the invention.

Figure 5 is a section on the line 5—5 of Figure 4.

Figure 6 is an elevational view of the locking pin of this second embodiment.

Referring first to Figures 1 through 3, there is illustrated end frames 10 composed of posts 11

and beams 12 welded together. The posts and beams are shown as tubular but they may be of any section.

In erecting the scaffold, the end frames are set up in spaced relation and connected by diagonal braces or stays 13. The braces may also be of any desired section but are shown as tubular. The frames are built up one on another to the desired height, dowels 14 being inserted in the upper ends of the posts of each frame and the lower ends of the posts of the next frame above are disposed thereon. The improved connection of this invention includes gusset plates 15 preferably of U-shape as shown in Figure 1, welded to the posts and beams in the corners of the frames and having slots 16 therein. Each slot has substantially parallel sides extending from the exposed edge of the plate and terminating at a point spaced from the edge. As shown in Figure 1, there are two gusset plates in each corner of the frame, the two plates being disposed parallel to each other forming wings of a substantially U-shaped member.

Each brace has a head 17 in the form of a square welded or otherwise formed on each end thereof. A flange 18 is welded at each end of the brace a short distance inwardly of the head. A square end portion 19 between the head 17 and flange 18 is formed on the brace such that the length of its sides is substantially equal to the width of the slot 16 in the gusset plate so that the end portion 19 will make a snug fit in the slot 16, thereby preventing rotation of the brace in the slot. A gravity locking member 20 is pivoted on the gusset plate 15 above the slot 16. The locking member 20 has an inclined portion 21 and hook portion 22 adapted to fall behind the edge of the head 17 (see Figure 2). A pin 23 supports the end of the locking member 20, to prevent its falling below the slot 16.

It will be apparent from the foregoing that the braces may be quickly and easily connected to the gusset plates. The end portion 19 of the brace is slid into the slot 16 whereupon the head 17 strikes the inclined portion 21 of the locking member 20 which slides across the edge of the head until the end portion 19 reaches the end of the slot 16 at which point the hook portion 22 drops behind the head 17. This locks the brace 13 in position in the slot 16, thus firmly connecting the braces to the end frames and constituting the latter a rigid self-sustaining structure.

When it is desired to dismantle the scaffold, the end frames may be disconnected and taken

down by removing the ends of the braces from the slots in the gusset plates. This is accomplished by lifting the locking member 20 to disengage the hook portion 22 from the head 17 of the brace and withdrawing the end portion 19 of the brace from the slot 16.

Figures 4, 5, and 6 show a slightly different form of locking arrangement. The gusset plate 24 is of U-shape having spaced parallel sides in which slots 25 are formed. The braces 13 cooperating therewith are identical with those described above excepting that a notch 26 is cut in at least one edge of the head 17 intermediate its ends. A downwardly curved aperture 27 is cut in each side of the gusset plate 24 above the slots 25 terminating adjacent the upper edge of the slot. A locking pin 28 is slidably mounted in these apertures so as to engage the notches 26 in the heads 17 of two opposite braces 13.

The function of the various parts of the two embodiments is the same with the exception of the locking members. In each case, however, the locking members operate by gravity to engage the head of the brace so as to prevent its removal from the slot in the gusset plate.

The connection of this invention is characterized by numerous advantages. It is simple, therefore cheaply manufactured. It is easy to operate, requiring no skill or experience. The use of tools is entirely eliminated, while at the same time the connection is strong and tight and not likely to be accidentally disconnected.

The only working part, the locking member, is permanently united with the gusset plate on the end frame so that it cannot be detached, lost, or misplaced.

Although we have shown and described only two forms of our invention, it will be understood that it may be otherwise embodied within the scope of the following claims.

We claim:

1. A separable connection for securing diagonal braces to the rectangular end frames of a knock-down scaffold comprising at least one gusset plate on the end frame having a substantially rectangular slot therein, a quadrangular end portion on the brace adapted to enter the slot, said end portion being substantially equal in thickness to the width of the slot whereby to engage the edges thereof to prevent rotation of the end portion in the slot, retaining means integral with the brace on either side of the end portion whereby the end portion is retained against longitudinal movement within the slot, gravity locking means on the gusset plate, and engaging means on at least one of the retaining means cooperating with the gravity locking means to hold the brace against removal from the slot.

2. A connection as defined by claim 1 characterized by a pair of gussets in each corner of said frame.

3. A connection as defined by claim 1 characterized by a pair of gussets substantially integrally connected forming a substantially U-shaped member.

4. A separable connection for securing diagonal braces to the rectangular end frames of a knock-

down scaffold comprising a pair of gusset plates in each corner of said frame, each of said gusset plates being parallel to the other, a substantially rectangular slot in each gusset plate, a quadrangular end portion on the braces adapted to enter a slot, said end portion being substantially equal in thickness to the width of the slot whereby to engage the edges thereof to prevent rotation of the end portion in the slot, retaining means integral with the brace on either side of the end portion whereby the end portion is retained against longitudinal movement within the slot, gravity locking means on the gusset plate, and engaging means on at least one of the retaining means cooperating with the gravity locking means to hold the brace against removal from the slot.

5. A connection as defined by claim 1 characterized by said gravity locking means being a hook pivoted to the gusset plate and adapted to drop behind one of the retaining means when the end portion of the brace is inserted into the slot.

6. A connection as defined in claim 1 characterized by the retaining means and the end portion being quadrangular in cross section, said end portion having one dimension substantially equal to the width of the slot.

7. A connection as defined in claim 1 characterized by the slot having parallel sides and the end portion of the brace being quadrangular in cross section having one dimension substantially equal to the distance between parallel sides of the slot.

8. A connection as defined by claim 1 characterized by said gravity locking means being a pin slidable in a downwardly curving aperture in the gusset plate terminating adjacent the upper edge of the slot and a notch in at least one retaining means engaged by the pin when said pin is at the lower terminus of the aperture.

9. A connection as defined by claim 3 characterized by said gravity locking means being a pin slidable in generally vertical apertures in the parallel gusset plates, said apertures terminating adjacent the upper edge of the slot, and a notch in at least one retaining means of each brace engaged by the pin when said pin is substantially at the bottom of the apertures.
